(57) **CLAIM**

The ornamental design for a receiver assembly for an auto-loading firearm, as shown and described.

DESCRIPTION

FIG. 1 is a front (muzzle end) isometric top view of a receiver assembly for an auto-loading firearm.

FIG. 2 is a rear (breach end) isometric bottom view thereof.

FIG. 3 is a right side elevational view thereof.

FIG. 4 is a left side elevational view thereof.

FIG. 5 is a front (muzzle end) elevation view thereof.

FIG. 6 is a rear (breach end) elevation view thereof.

FIG. 7 is a top plan view thereof.

FIG. 8 is a bottom plan view thereof.

FIG. 9 is another front isometric top view thereof.

FIG. 10 is another rear isometric bottom view thereof.

FIG. 11 is another left side elevational view thereof.

FIG. 12 is another right side view thereof.

FIG. 13 is another front elevation view thereof.

FIG. 14 is another rear elevation view thereof.

FIG. 15 is another top plan view thereof; and,

FIG. 16 is another bottom plan view thereof.

The broken lines in the figures illustrate environment and unclaimed parts, and form no part of the claimed design.
